WELL PLUGGING AND WHIPSTOCKING

Donovan B. Grable, Long Beach, and John M. Jackson, Santa Monica, Calif.

Application August 10, 1945, Serial No. 610,062

22 Claims. (Cl. 255—1.6)

1

This invention has to do with open (uncased) hole plugging and whipstocking operations in oil wells, and has for its general object to provide improvements in open hole plugs and whipstocks, and methods for their placement and use, having various important advantages over the types of plugs, whipstocks and methods heretofore employed.

Considering first the conventional practices in open hole whipstocking, the customary procedure has been to first place in the uncased hole a cement plug to serve as a footing for a whipstock later to be run into the well after the cement is set. This practice has involved difficulties from standpoints both of the security of the footing and the length of time necessarily consumed. The well bore wall frequently is coated with mud to a degree rendering it difficult to obtain a properly strong and load sustaining bond between the cement plug and the formation. Thus failure of the bond to support the plug weight or the subsequently applied load necessitates a replugging operation. After the plug cement is placed in the hole it is necessary to wait a considerable period of time for the cement to harden sufficiently to serve as a firm or hard footing for the whipstock, thus entailing considerable expense in view of the idleness of equipment and workers while the cement is reaching a hardened condition.

One major object of the invention is to provide improved methods and equipment whereby in virtually one continuous sequence, the whipstock may be oriented and firmly set in the hole, followed immediately by offset drilling. The invention contemplates the use of a novel whipstock comprising a plug body particularly designed for use in open hole by the provision of expandable means adapted to penetrate the formation and securely anchor the whipstock in place. As will appear, the whipstock may be run into the well on a pipe string carrying a cutting tool to which the whipstock is detachably connected, and the body of the whipstock is provided with an initially open passage permitting fluid circulation through, and up around the whipstock during its lowering to its proper depth. With provision thus made for mechanically interlocking the plug with the formation, no difficulties are encountered by reason of mud cake on the bore wall. In fact, maintenance of the described fluid circulation, together with permissible proximity of the plug to the bore wall, permits substantial removal of the mud film.

After being set in position as described, the whipstock may be adequately supported to permit immediate starting of deflected drilling.

2

However, it may be preferred, for various reasons, first to cement the plug in place, or to form a cement plug in the hole below the whipstock. Accordingly, after the whipstock is anchored to the formation, cement may be pumped down through the pipe string and whipstock to a discharge location directly or some distance below the plug body. When permitted by space between the whipstock and bore wall, the cement may fill the space and form a hard bond with the formation.

With the whipstock thus anchored in place, with or without cementing, the connection between the whipstock and cutting tool may be released and offset drilling immediately started. As will appear, for drilling purposes a full size bit may be used, it being unnecessary to first drill an offset rat hole as in customary practice.

A further feature of the invention is the use in conjunction with a whipstock or plug, of an extended tail pipe through which circulation and cement discharge may be maintained to any desired depth below the whipstock or plug. As will later appear, this feature may be employed to advantage in cementing about and drilling past a fish lodged at an intermediate location in the well.

While reference has been made to the use of a combined plug and whipstock, the invention also contemplates an improved open hole plug having the described structural and operative characteristics except those features attributable to the whipstock as such. The hereinafter described form of simple plug may be used, among various purposes, as a footing for a whipstock to be subsequently run into the well, the plug itself having the characteristic advantage, with or without cementing, and providing immediately upon being expanded into the formation, a strong and hard surface whipstock support. Accordingly, immediately after setting of the plug, the whipstock may be run into the well, oriented, and offset drilling started.

All of the aforementioned features and objects of the invention, as well as many additional details, will be explained to better advantage in the following description of the typical embodiments illustrated by the accompanying drawings, in which:

Fig. 1 is a view showing the whipstock in vertical section detachably connected to a drill bit, the formation anchoring means being shown in released position;

Fig. 2 is a similar view showing the whipstock anchored to the formation and disconnected from the drill bit;

Fig. 3 is a fragmentary view showing the

bottom portion of the whipstock or plug with its tail pipe run down past a fish and the assembly cemented in place;

Fig. 4 is a fragmentary sectional view showing the whipstock releasably connected to a core drill or baller;

Fig. 5 illustrates a further variation of the invention in the form of a simple plug;

Fig. 6 is an enlarged fragmentary section illustrating the formation penetrating pins in retracted position; and

Fig. 7 is a fragmentary view showing one of the pins projected and locked into the formation.

Referring first to Figs. 1 and 2 illustrating one embodiment of the invention in an open hole whipstock, the whipstock comprises an elongated cylindrical body generally indicated at 10, which preferably is made of a suitable drillable material, typically concrete 11. The upper end of the body may be formed as a metallic whipstock head 12, which may also be of drillable material but of sufficient hardness to deflect or whipstock the cutting tool, except under circumstances where it may be desired to so confine or direct a type of cutting tool that will drill through the plug, if for any reason disintegration of the plug is desired. The body 10 contains a longitudinal fluid passage 13 formed typically by an upper pipe section 14 joined by coupling 15 with any desired number of sections 16 interconnected by couplings 17. A lower pipe section 18 is positioned in the plug at an inclination with the vertical axis of the plug, as and for the purposes later described. Section 18 is connected by couplings 19 and 20 with a bottom connector 21 which initially contains a frangible seat 22 held in place by the fitting 23.

Referring to Figs. 6 and 7, the body 10 contains a vertical series of fluid pressure operable formation penetrating elements or assemblies, generally indicated at 24, which may be provided in any suitable number and arrangement as required for firm anchoring and stabilization of the body within the bore hole. Each of the assemblies 24 is shown typically to comprise four cylinders 25 arranged at 90° and threaded at 26 into the coupling 17. The outer ends of the cylinders 25 are closed by heads 27, and the cylinders contain pistons 28 carrying pins 29 which are radially projectible through openings 30 into the formation 31 by fluid pressure communicated from passage 13 through the coupling openings 32 to the pistons 28. In order to assure retention of the pins 29 in their expanded or formation penetrating positions, see Fig. 7, the pins may carry spring-expanded latch elements 33 which are passable through the openings 30 and thereafter caused to expand and engage the heads 27 to lock the pins against inward movement.

The whipstock is lowered into the uncased well bore 35 on a pipe string 36 carrying a cutting tool, for example the drill bit 37, to which the whipstock is releasably connected by a joint 38 capable of supporting the whipstock and transmitting thereto turning movement of the pipe string, and capable also of conducting fluid from the pipe string into the passage 13. Typically the joint 38 is shown to consist of a drillable pipe 39 having at 40 a left-hand thread connection with the bit, and carrying on its lower end a head 41 having splined engagement at 42 within the pipe section 14. By reference to Fig. 2 it will be observed that the relative lengths of the pipes 14 and 39 are such that when the latter is disconnected from the drill bit, it may drop into and be

received within pipe 14 below the deflecting face 43 of the whipstock. As the drawing shows, while the whipstock is being lowered, it is supported by the interengagement of shoulder 44 and 45 respectively on the pipes 41 and 14.

In operation, the whipstock plug is lowered into the bore 35 on the pipe string 36 in the condition illustrated by Fig. 1. Assuming the whipstock to be lowered to proper depth, it may then be desirable to orient the body 10 to bring the whipstock face into the position of horizontal angularity required for deflection of the bit 37 in the proper direction. For this purpose, a surveying instrument, conventionally indicated at 46 is lowered on cable 47 through the pipe string and joint 38 into the inclined section 18 of the plug passage. The instrument 46 may be of any of the known types, for example a so-called single shot, capable of indicating or measuring the horizontal angular direction of the passage inclination, and therefore the horizontal angular position of the whipstock face 43, since the latter has a fixed relation to the inclination of the pipe section 18. By rotational adjustment of the whipstock in the well bore, it may be properly oriented as determined by readings of instrument 46.

Ordinarily it will be desirable to maintain fluid circulation through the whipstock during a portion or the entirety of its travel while being lowered to setting position within the well. Circulation is maintained by pumping mud through the drill pipe, joint 38 and the plug passage 13. It may be advantageous for such purposes as later described, to circulate the fluid or cement to a discharge location substantially below the lower end of the whipstock. For this purpose, the body 10 may carry an extended depending tail pipe 50 connected to the coupling 21. Maintenance of fluid circulation of course tends to facilitate lowering of the whipstock within an otherwise restricted well, and to clean out the space between the whipstock body and the bore wall. At this point it may be mentioned that in order to assure maximum support and stability of the plug when anchored or set in the hole, the plug diameter may be made to correspond closely to the well bore diameter. In some instances the plug may have a snug or even fairly tight fit within the bore.

Assuming the whipstock to be properly oriented in the well, an object such as the metal ball 48 may be dropped through the pipe string and plug passage to seat upon and substantially close or restrict the opening 49 in the seat 22, to permit the development of sufficiently high fluid pressure in the passage 13 to expand the pins 29 into the formation as shown in Fig. 2. Thereafter, by further increasing the fluid pressure, the frangible seat 22 may be ruptured and the ball 48 blown out through the plug or tail pipe to again open the passage 13.

With the whipstock thus anchored in the hole, whipstock drilling may be started by disconnecting the bit from pipe 39. Ordinarily however it is preferred first to cement the plug in place. Accordingly, after displacement of the ball 48, cement may be pumped down through the plug, and tail pipe if used, into the well bore below the plug, and if desired in quantities such that the cement will flow partially or entirely up around the anchored plug. The latter thus is set to permit immediate whipstock drilling, a feature of considerable importance, since in contradistinction to the conventional practices and

Limitations, it is unnecessary to await initial or any stage setting of the cement.

By reverse rotation of the pipe string, pipe 38 is unscrewed from the drill bit and permitted to drop into the whipstock body as shown in Fig. 2. If for any reason the pipe 39 should become lodged in raised position, it can be drilled away by the bit. The anchored whipstock affords an immediate rigid and hard or positive deflector for directing the bit in continued offset drilling in accordance with the direction of the whipstock face 43.

Fig. 3 illustrates an adaptation of the invention to be employed for the purpose of by-pass or deflected drilling past an object or fish lodged at an intermediate location in the well bore. Conventionally, the fish 51 is shown to consist of a metal object, tool or pipe section lodged above the bottom of the well bore 35, and having a size or position permitting the tail pipe 50 to be lowered past at least a portion of, and preferably the entire fish. By pumping cement down through the whipstock and tail pipe positioned as in Fig. 3, the fish, or both the fish and the whipstock, may be cemented in the hole. Thereafter, by offset drilling as previously described, the bit may be deflected past the plug and fish, and if desired brought back into the bore 35 below the fish, thus completely by-passing the latter.

Fig. 4 illustrates a variational adaptation of the invention, involving the use of the whipstock in combination with a core drill or barrel, as distinguished from the drill bit 31. Here the pipe 39 is shown to have a left hand thread connection at 53 with the conventionally illustrated core barrel or drill 54, the latter being of any suitable type capable of cutting around and receiving a core sample for removal to the ground surface. After disconnection from the pipe 39, the core drill may be deflected to receive a core sample of the formation taken at the location of the whipstock and in the course of the offset hole to be drilled.

The described use of the whipstock in conjunction with a core barrel or drill provides new practice and procedure in formation exploration. The suitability of the formation for offset drilling at the location or orientation corresponding to the initial setting of the whipstock, may be ascertained by taking the core sample as described. If the characteristics of the core show the formation to be unsuited for the purposes of the contemplated offset drilling from the set whipstock, the latter may be drilled out of the hole and a second whipstock set in the well at a different location, e. g. lower depth, or at a different orientation, and a second core sample taken to again investigate the formation. This general procedure may be repeated as many times as necessary to finally locate the whipstock for drilling through formation having the desired or favorable characteristics.

In Fig. 5 we show an embodiment of the invention in a simple plug 55 detachably secured at 56 to a pipe string 57. As will be understood without necessity for further illustration and description, the bottom portion of the plug below that illustrated in Fig. 5 may correspond to the form of Fig. 1, and the operations involved in the lowering, circulating, orienting, anchoring and cementing of the plug may be the same as the previously described steps and operations. The purpose of the plug 55 may be simply to close the open hole bore for any purpose requiring its plugging.

or the plug 55 may be set in the hole as a support or footing for a conventional and independently run-in whipstock. In this connection, the plug affords a distinct advantage over present tools and procedures for open hole whipstocking, in that immediately upon being anchored and set in the well, it provides a firm footing for whipstock operations.

Finally it may be observed with reference to 10 the composition of the described whipstock, that the material of which it is made may have varying hardness depending upon or in predetermined relation to the hardness of the formation in which it is set. To assure positive deflection of the bit to be deflected into relatively hard formations, the hardness of the whipstock body materials may be appropriately or correspondingly increased, and conversely where the formation is relatively soft.

We claim:

1. A plug adapted to be lowered on a pipe string into an uncased hole, a whipstock face on the plug, said plug comprising a vertically elongated body containing a normally open longitudinal passage having at least one portion inclined with respect to the vertical axis of the body for reception of an instrument to determine the orientation of the plug, fluid circulation being permitted downwardly through said passage while the plug is being lowered in the well, and fluid pressure actuated means operable to penetrate the formation to hold the plug in set position within the hole.

2. A well plug adapted to be lowered on a pipe string into an uncased hole, comprising a body having a top whipstock end and containing a passage for conducting fluid through the plug, a formation cutting tool carried by said pipe string, tubular means releasably connecting said tool with the plug and said passage, and fluid pressure actuated means operable to penetrate the formation to hold the plug in position in the hole.

3. A well plug adapted to be lowered on a pipe string into an uncased hole, comprising a body having a top whipstock end and containing a passage for conducting fluid through the plug, a formation cutting tool carried by said pipe string, tubular means releasably connecting said tool with the plug and said passage and operable to rotate the plug upon rotation of the pipe string, and fluid pressure actuated means operable to penetrate the formation to hold the plug in position in the hole.

4. A well plug adapted to be lowered on a pipe string into an uncased hole, comprising a body having a top whipstock end and containing a passage for conducting fluid through the plug, a formation cutting tool carried by said pipe string, tubular means releasably connecting said tool with the plug and said passage, a portion of said passage being inclined with respect to the vertical axis of the body for reception of an instrument to determine the orientation of the plug, and fluid pressure actuated means operable to penetrate the formation to hold the plug in position in the hole.

5. A well plug adapted to be lowered on a pipe string into an uncased hole, comprising a body having a top whipstock end and containing a passage for conducting fluid through the plug, a formation cutting tool carried by said pipe string, tubular means releasably connecting said tool with the plug and said passage, fluid pressure actuated means operable to penetrate the formation to hold the plug in position in the hole, and

a tail pipe communicating with said passage and depending below the plug.

6. A well plug adapted to be lowered on a pipe string into an uncased hole, comprising a body having a top whipstock end and containing a passage for conducting fluid through the plug, a formation cutting tool carried by said pipe string, tubular means releasably connecting said tool with the plug and said passage, fluid pressure actuated means operable to penetrate the formation to hold the plug in position in the hole, and means for temporarily closing fluid discharge through said passage.

7. A well plug adapted to be lowered on a pipe string into an uncased hole, comprising a body having a top whipstock end and containing a passage for conducting fluid through the plug, a formation cutting tool carried by said pipe string, tubular means made of drillable metal releasably connecting said tool with the plug and said passage, and fluid pressure actuated means operable to penetrate the formation to hold the plug in position in the hole.

8. A well plug adapted to be lowered on a pipe string into an uncased hole, comprising a body having a top whipstock end and containing a passage for conducting fluid through the plug, a formation cutting tool carried by said pipe string, tubular means releasably connecting said tool with the plug and said passage, and fluid pressure actuated means operable to penetrate the formation to hold the plug in position in the hole, said tubular means being movable down into the plug below said whipstock end upon disconnection from said tool.

9. A well plug adapted to be lowered on a pipe string into an uncased hole, comprising a body having a top whipstock end and containing a normally open passage permitting fluid circulation through the plug while being lowered, means for substantially closing fluid discharge through said passage, means then radially expansible by the fluid pressure in said passage to penetrate the formation and hold the plug in set position within the hole, a formation cutting tool carried by said pipe string, tubular means releasably connecting said tool with the plug and said passage, said connecting means being vertically movable relative to the body and being operable to rotate the plug upon rotation of the pipe string, cement being flowable through said connecting means and passage below and around the plug, and the connecting means then being disconnectable from the cutting tool.

10. A plug adapted to be lowered on a suspension means and set in an uncased hole, said plug including a vertically elongated body having an upper whipstock portion and containing a longitudinal passage having at least one portion inclined with respect to the vertical axis of the body for reception of an instrument to determine the orientation of said whipstock portion of the body, said passage extending from its top in a course of downward directness permitting the instrument to be lowered by gravity into said inclined portion.

11. A plug adapted to be lowered on a pipe string and set in an uncased hole, said plug comprising a vertically elongated body having an upper whipstock portion and containing a longitudinal passage having at least one portion inclined with respect to the vertical axis of the body for reception of an instrument run down through the pipe string to determine the orientation of said whipstock portion of the body, said passage

5

extending from its top in a course of downward directness permitting the instrument to be lowered by gravity into said inclined portion and means releasably connecting said passage and plug with the pipe string.

12. A whipstock adapted to be lowered on a pipe string and set in an uncased hole, comprising a vertically elongated body of drillable material containing, a tube in said body and connectible with said pipe string, a portion of the tube being inclined with respect to the vertical axis of the body for reception of an instrument to determine the orientation of the body, said tube extending from its top in a course of downward directness permitting the instrument to be lowered by gravity into said inclined portion thereof.

13. A whipstock adapted to be lowered on a pipe string and set in an uncased hole, comprising a vertically elongated body of drillable material containing, a tube in said body and connectible with said pipe string, a straight portion of the tube being coaxial with the body and another portion of the tube being inclined with respect to the vertical axis of the body for reception of an instrument to determine the orientation of the body, and means in the body opposite said straight portion of the tube and operable by the fluid pressure therein to penetrate the formation and anchor the body therein.

14. A plug adapted to be lowered on a pipe string into an uncased hole, comprising an initially open passage permitting fluid circulation downwardly through the plug while being lowered, means expansible by fluid pressure in said passage to penetrate the formation and hold the plug in set position within the hole, and a closure below said expansible means for temporarily substantially closing downward fluid discharge through said passage to actuate said expansible means and displaceable to again permit fluid flow downwardly through said passage and upwardly about the plug after penetration of the formation by said expansible means.

15. A plug adapted to be lowered on a pipe string into an uncased hole, comprising an initially open passage permitting fluid circulation downwardly through the plug while being lowered, a closure for substantially closing downward fluid discharge through said passage, and means above said closure then radially expansible by the fluid pressure in said passage to penetrate the formation and hold the plug in set position within the hole, said closure being displaceable out of the plug and into the well to permit fluid flow downwardly through said passage and upwardly about the plug after penetration of the formation by said expansible means.

16. A plug adapted to be lowered on a pipe string into an uncased hole, comprising an initially open passage permitting fluid circulation downwardly through the plug while being lowered, a closure for substantially closing fluid discharge through said passage, means above said closure then radially expansible by relatively low fluid pressure in said passage to penetrate the formation and hold the plug in set position within the hole, said closure being displaceable in response to the communication of relatively high fluid pressure to said passage to permit fluid flow downwardly through said passage and upwardly about the pipe.

17. A plug adapted to be lowered on a pipe string into an uncased hole, comprising an initially open passage permitting fluid circulation

downwardly through the plug while being lowered, a closure for substantially closing fluid discharge downwardly through said passage, means above said closure then radially expansible by relatively low fluid pressure in said passage to penetrate the formation and hold the plug in set position within the hole, said closure being displaceable in response to the communication of relatively high fluid pressure to said passage to permit fluid flow downwardly through said passage and upwardly about the pipe, and an extended tail pipe depending from the plug below said closing means.

18. A plug adapted to be lowered on a pipe string into an uncased hole, comprising an initially open passage permitting fluid circulation downwardly through the plug while being lowered, releasable means for closing said passage, and fluid pressure actuated means above said closing means operable to penetrate the formation to hold the plug in set position within the hole, said means comprising a plurality of radially expansible pins having inner piston ends exposed to the fluid pressure in said passage and outer ends adapted to penetrate the formation, and means for locking said pins in expanded positions.

19. A plug adapted to be lowered on a pipe string into an uncased hole, comprising an elongated concrete body, tubular means extending longitudinally through the plug and connected to said pipe string, fluid circulation being permitted downwardly through a passage formed by said tubular means while the plug is being lowered in the well, radial cylinders communicating with said passage, expansible pins having inner piston ends contained within said cylinders and outer ends adapted to penetrate the formation, means below said cylinders for substantially closing fluid circulation through said passage, said pins then being radially expansible by relatively low fluid pressure applied to said pistons, said passage closing means being displaceable in response to the communication of relatively high fluid pressure to said passage to permit fluid flow downwardly through said passage and upwardly about the pipe.

20. A plug adapted to be lowered on a pipe string into an uncased hole, comprising a concrete body having a top metallic whipstock end and containing a tube forming an initially open passage permitting fluid circulation downwardly through the plug while being lowered, a closure for substantially closing downward fluid dis-

charge through said passage, and fluid pressure actuated means above the closure then operable to penetrate the formation to hold the plug in set position within the hole, said closure being displaceable to permit fluid flow downwardly through said passage and upwardly about the plug after penetration of the formation by said fluid pressure actuated means.

21. A plug adapted to be lowered on a pipe string into an uncased hole, comprising a non-metallic body having a top metallic whipstock end and containing a metal tube forming an initially open passage permitting fluid circulation through the plug while being lowered, a closure for substantially closing downward fluid discharge through said passage, and fluid pressure actuated means above the closure then operable to penetrate the formation to hold the plug in set position within the hole, said closure being displaceable to permit fluid flow downwardly through said passage and upwardly about the plug after penetration of the formation by said fluid pressure actuated means.

22. A plug adapted to be lowered on a pipe string into an uncased hole, comprising an initially open passage permitting fluid circulation downwardly through the plug while being lowered, frangible closure seat means in said passage, a drop-in closure adapted to engage said seat means and temporarily close said passage against downward circulation of fluid, and means then expansible by the fluid pressure in said passage to penetrate the formation and hold the plug in set position within the hole, said seat means being rupturable by the fluid pressure after actuation of said expansible means to again permit downward circulation of fluid.
